UNITED STATES PATENT OFFICE

RICHARD H. WHITEHEAD, OF NEW HAVEN, CONNECTICUT, ASSIGNOR TO THE NEW HAVEN CLOCK COMPANY, OF NEW HAVEN, CONNECTICUT, A CORPORATION

DESIGN FOR A CLOCK CASE

Application filed July 25, 1929. Serial No. 32,201. Term of patent 14 years.

To all whom it may concern:

Be it known that I, RICHARD H. WHITEHEAD, a citizen of the United States, residing at New Haven, in the county of New Haven and State of Connecticut, have invented a new, original, and ornamental Design for a Clock Case, of which the following is a specification, reference being had to the accompanying drawing, forming part thereof.

Fig. 1 is a face view of a clock-case showing my new design; and

Fig. 2 is a side view of the same.

I claim:

The ornamental design for a clock-case as shown.

RICHARD H. WHITEHEAD.
